CLAIM

The ornamental design for a stowable table and frame for a canopy for a vehicle, truck, light delivery vehicle or similar vehicle as shown and described.

DESCRIPTION

FIG. 1 is a front elevation view of a stowable table and frame for a canopy for a vehicle, truck, light delivery vehicle or similar vehicle of my new design, shown in a stowed configuration within the environment of a canopy for a vehicle, truck, light delivery vehicle or similar vehicle;

FIG. 2 is a bottom plan cross-section view thereof taken along line 2-2;

FIG. 3 is a right side cross section view thereof taken along line 3-3;

FIG. 4 is a perspective view thereof;

FIG. 5 is a front elevation view thereof, shown in an operable configuration within the environment of a canopy for a vehicle, truck, light delivery vehicle or similar vehicle;

FIG. 6 is a bottom plan cross-section view thereof taken along line 6-6;

FIG. 7 is a right side cross section view thereof taken along line 7-7;

FIG. 8 is a perspective view thereof; and,

FIG. 9 is a right side cross section view thereof taken along line 7-7, shown with the table in a partially extracted position of operable configuration within the environment of a canopy for a vehicle, truck, light delivery vehicle or similar vehicle.

(Continued)

The broken lines depict environment of a canopy for a vehicle, truck, light delivery vehicle or similar vehicle that form no part of the claimed design.
